(74) *Attorney, Agent, or Firm* — Owen G. Behrens; Smith & Hopen, P.A.

(57) **CLAIM**

The ornamental design for a milling machine chip guard as shown and described.

DESCRIPTION

FIG. 1 is a top plan view of a second embodiment of a milling machine chip guard showing the new design; FIG. 2 is a right side perspective view of the milling machine chip guard as shown in FIG. 1; FIG. 3 is a right side elevation view of the milling machine chip guard as shown in FIG. 1; FIG. 4 is a left side perspective view of the milling machine chip guard as shown in FIG. 1; FIG. 5 is a bottom plan view of the milling machine chip guard as shown in FIG. 1; FIG. 6 is a front elevation view of the milling machine chip guard as shown in FIG. 1; and, FIG. 7 is a back elevation view of the milling machine chip guard as shown in FIG. 1. The evenly-dashed broken line(s) showing portions of a milling machine chip guard form no part of the claimed design.

1 Claim, 7 Drawing Sheets
